DISPENSER FOR LIQUIDS OR FLUIDISED POWDERS

Derrick R. Gatley, Reading, England, assignor to Graviner (Colnbrook) Limited, London, England, a British company

Filed Apr. 1, 1968, Ser. No. 11,252

Term of patent 14 years

Int. Cl. D23—01; D9—01

U.S. Cl. D23—17

Fig. 2.

Fig. 1.

Fig. 3.

Fig. 4.

FIGURE 1 is a front elevational view of a dispenser for liquids or fluidised powders showing my new design; FIGURE 2 is a top plan view thereof;

FIGURE 3 is an elevational view of one side thereof, the opposite side being a mirror image of FIGURE 3; and

FIGURE 4 is a rear elevational view thereof.

I claim:

The ornamental design for a dispenser for liquids or fluidised powders, as shown and described.
